CLAIM

The ornamental design for an air outlet of air conditioner for vehicle, as shown and described.

DESCRIPTION

FIG. 1 is a perspective view of a first embodiment of an air outlet of air conditioner for vehicle showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view thereof depicted in a secondary position of use;

FIG. 9 is a front elevation view thereof depicted in the secondary position of use;

FIG. 10 is a rear elevation view thereof depicted in the secondary position of use;

FIG. 11 is a perspective view of a second embodiment of an air outlet of air conditioner for vehicle showing our new design;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan view thereof;

FIG. 17 is a bottom plan view thereof;

FIG. 18 is a perspective view thereof depicted in a secondary position of use;

FIG. 19 is a front elevation view thereof depicted in the secondary position of use; and,

FIG. 20 is a rear elevation view thereof depicted in the secondary position of use.

(Continued)

The broken lines depict portions of the air outlet of air conditioner for vehicle that form no part of the claimed design.
